UNITED STATES PATENT OFFICE.

HETTIE J. DUDLEY, OF RICHMOND, VIRGINIA.

DESIGN FOR A FANCY BAG.

Application filed May 16, 1923. Serial No. 6,170. Term of patent 7 years.

To all whom it may concern:

Be it known that I, HETTIE J. DUDLEY, a citizen of the United States, residing at Richmond, in the county of Henrico and State of Virginia, have invented a new, original, and ornamental Design for Fancy Bags, of which the following is a specification, reference being had to the accompanying drawing, forming part thereof.

The figure is a perspective view of the fancy bag showing my new design.

I claim:

The ornamental design for a fancy bag as shown.

Signed at Richmond, in the county of Henrico, State of Virginia, this 14th day of May, 1923.

HETTIE J. DUDLEY.
